TRIGGER SAFETY LATCH FOR FIREARMS

Jessie T. Ivy, 523 Henderson St., Seattle, Wash.

Filed Oct. 28, 1958, Ser. No. 770,196

2 Claims. (Cl. 42—70)

This invention relates to safety latches as applied to rifles, revolvers and the like, to prevent accidental firing. More particularly, it pertains to safety latches that are directly associated with the trigger and the pistol grip or hand grip portion of a rifle, revolver or the like.

The present application is a continuation in part of my co-pending application filed on November 15, 1957, under Serial No. 696,738.

It is the principal object of this invention to provide a practical, effective and novel safety latch mechanism whereby accidental firing of the rifle or fire arm to which it is applied, that might be caused by a blow or force applied against the trigger, is prevented. Furthermore, to provide a safety latch mechanism that is adapted to be released by the same hand that grasps the pistol grip portion of the present device as applied to the frame of the fire arm and by which the trigger is pulled for firing.

It is also an object of the present invention to provide a safety latch mechanism contained by the pistol grip and which can only be released by the application of pressure against it in a direction opposite to the direction of pull applied to the trigger for firing.

Further objects and advantages of the invention reside in the details of construction and combination of its parts and in their mode of operation, as will hereinafter be fully described.

In accomplishing the above mentioned and other objects of the invention, I have provided the improved details of construction, the preferred forms of which are illustrated in the accompanying drawings, wherein:

Fig. 1 is a side view of the pistol grip and trigger guard portion of a rifle, or the like with parts broken away or shown in section to illustrate the application of the present safety latch mechanism thereto; the latch mechanism here being shown in normal latched position.

Fig. 2 is a similar view showing the pistol grip latch in that depressed and released position that permits the trigger to be pulled for firing the rifle.

Fig. 3 is a cross-section taken through the pistol grip on the line 3—3 in Fig. 1.

Fig. 4 is a sectional detail, taken on line 4—4 in Fig. 1, showing details of the pistol grip latch mounting.

Fig. 5 is a perspective view of the sliding latch block of the latch mechanism.

Referring more in detail to the drawings:

In these views, 10 designates that portion of the wood stock of a rifle to which a trigger guard 11 and a pistol grip, which is herein designated in its entirety by reference numeral 12, are attached. The pistol grip, as here shown may be like or similar to that disclosed in my U.S. Patent No. 2,832,166 issued on April 29, 1958.

As here shown, the pistol grip comprises a one-piece frame member 12f of the usual pistol grip shape, provided with a body chamber 13 of substantial size in which the latch mechanism embodied by this invention, is contained; this chamber being closed at its opposite sides by knurled or otherwise decorated plates 14—14 that may

2

be secured in place by the usual application of screws, such as that shown at 15 in Fig. 3 which extends through chamber 13 approximately at its center.

It is to be observed that the upper and forward portion 5 of the pistol grip frame 12f is fitted to the curvature of the rearward end portion of the trigger guard; the trigger guard being formed at that end with a rearwardly projecting part terminating in a head 16 that is fitted in a socket 17 formed in the top and forward edge portion of the frame 12f to receive it. It is preferred, in this assembly of parts, that the joint between the fitted edges of the trigger guard and pistol grip frame be covered, at each side, by fittings such as that shown at 19 in Fig. 7; these fittings being secured in place by screws, as indicated at 20, and the top edges of the plates 14 being fitted thereto.

In the present illustrations, 25 designates the trigger by which the rifle is fired. This may be mounted in the rifle frame in any practical manner with its lower end extended into the trigger guard. The trigger must be pulled rearwardly as from the normal position in which it is shown in dotted lines in Fig. 2 to the full line position, for firing the rifle.

Formed through that forward portion of the pistol grip frame 12f that is fitted to the trigger guard, is a bore 28 which is in axial alignment with a continuing bore 29 in the rear portion of the trigger guard. A pin 30 is slidably fitted in these bores, 28 and 29, with its forward end engaged against the back side of the lower end portion 20 of the trigger 25 and its rearward end portion extended well into the upper end portion of the chamber 13 of the pistol grip frame where it is contained within a channel 31 formed in an arm 32' that extends upwardly from a forwardly and rearwardly movable latch block 32. A nut 34, that is adjustably threaded onto the pin 30 engages against the front face of the block arm 32'.

The block 32 is normally held in the position shown in Fig. 1 by the present hand grip latch lever 35 which is shown to be mounted in the lower end portion of the 30 pistol grip chamber 13. At its lower end the latch lever 35 is pivotally mounted by a supporting pin 36 on which it swings forwardly and rearwardly at its upper end. Between its ends, this lever is formed with a rearwardly projecting press portion 35x that is contained in and projects 40 through and rearwardly from a slot 38 formed in the rear edge member of the pistol grip frame 12f. Normally, the press portion 35x projects to the extent shown in Fig. 1, and when the lever is in this position, the upper end portion of the lever abuts against the under surface of a rearward end portion 32a of the latch block 32 and thus retains the block in its forward position. A leaf spring 40, that is attached to the lower end portion of the latch lever 35, extends upwardly along the latch lever and is then curved forwardly to bear against the bolt 15, thus 45 to yieldingly hold lever 35 in the latch block locking position of Fig. 1. The normal position of the block 32 is that in which it is shown in Fig. 1. When in that position, the pin 30 engages firmly at its forward end against the lower end portion of the trigger and positively prevents its being pulled or being actuated by any blow that 50 would result in firing the rifle should it be loaded and cocked for firing.

It is to be observed also by reference to Fig. 1 that the latch block 32, when in locked position is supported at its 55 forward end upon a rearwardly and downwardly curving portion of frame 12f with its forward end surface abutted against a flat surface of the chamber wall thus to limit the forward movement of the block. The rear end portion of the block has a top surface 32t, as shown in Fig. 5, that is slidably along an opposingly facing surface of the chamber 13. It is also to be observed in Fig. 1 that

the under surface 32a of the rear end portion of block 32 is upwardly and rearwardly curved and is engaged by a surface 35e at the upper end of lever 35 that is curved about the axis of pivot pin 36. The block 32 is urged forwardly at all times by a small coil spring 44 that has its end portions contained in sockets 45 and 46 formed in the rear face of the arm 32' of the block and the opposedly related face of the chamber 13.

The pin 30, as contained in the bores 28 and 29 and also in channel 31 of the upwardly extended arm 32' of the block has the nut 34 threaded thereon and so adjusted against the forward face of the arm 32' to dispose the forward end of the pin against the backside of the trigger. This adjustment is then secured by a lock nut 49 that is tightened against nut 34.

With the latch parts in the positions shown in Fig. 1, the trigger 25 cannot be pulled rearwardly to firing position. This can be done only when the latch lever 35 has been actuated to its released position as seen in Fig. 2 to disengage it from the latch block.

The significance of placing the latch lever 35 in the backside of the pistol grip 12 resides in the fact that any object that might accidentally strike against it and depress it to a released position would not be apt to act in the opposite direction against the trigger 25 at the same time.

In using the rifle, or any other similar firearm so equipped with this grip and safety latch mechanism, the user, in getting ready to fire, tightens his hand hold about the grip 12 and in doing this depresses the latch lever 35 to the position shown in Fig. 2, thus disengaging its upper end from the latch block 32, then when ready to fire, pulls the trigger. This moves the block 32 to the position shown in Fig. 2. The instant the trigger pull is released, the coil spring 44 moves the latch block 32 back to normal position as in Fig. 1, and with release of tight hold in the grip 12, the latch lever 35 is moved back to its block locking position by spring 40.

For assembly purposes, the rear wall of chamber 13 is formed, at a location aligned with pin 30, with a socket 47 into which the rear end of the pin can be disposed in order that its forward end will not project from bore 28 and interfere with the assembling of the frame 12f with the trigger guard. Also, the channel 31, as formed in block 32, opens to a side of the block in order that the block can be laid into place after the pin 30 has been placed in position. The assembling of the latch parts within the frame 12f is done before both of the facing pieces 14 have been placed in position on the frame.

As a detail of construction and method of assembly, the pivot pin 36, which mounts the lower end of latch lever 35 thereon, projects through the lower end of the lever. With the pin so applied to the lever, the lever end is brought into mounting position, as shown in Figs. 1 and 4. Then washers 50 are fitted to the ends of the pin and seated in circularly curved seats 51, flush with

the opposite faces of the frame 12f. When the face plates 14-14 are applied to the frame, they secure the assembly, as will be understood by reference to Fig. 4.

It is believed that the present invention is unique in its combination and relationship of parts, and in the fact that the safety mechanism is contained entirely in the pistol grip portion and can be applied to any firm arm of the common types without requiring any deletion or change in their operating parts.

10. What I claim as new is:

1. The combination with a firearm of the character described, having a pull trigger for firing it, of a chambered piston grip fixed to the frame immediately rearward of said trigger in position to be tightly gripped for firing, by the hand from which the trigger pulling finger extends; a safety latch mechanism for said trigger comprising a block slidably mounted in the upper end portion of said chambered piston grip for limited movement in directions from and toward the finger engaging portion of the trigger, yieldable means acting against said block and urging it forwardly, a pin slidably mounted in said piston grip in abutting engagement at one end with said block and normally urged thereby into contact at its other end with the trigger to prevent its being pulled for firing, a latch lever contained in the lower portion of the chambered piston grip and yieldingly pivotally mounted therein at its lower end with its upper end portion normally yieldably disposed in the path of rearward movement of said block as a stop therefor and to positively retain said block and pin in trigger holding position; said lever having a press portion between its ends projecting rearwardly from the piston grip whereby said lever will be actuated, incident to tightening the hand hold about the piston grip preparatory to firing, to swing its upper end portion from holding contact with said block thus to free the block and pin for rearward movement of the trigger for firing.

2. The combination recited in claim 1 wherein said block is formed with a channel opening laterally from the block in which the rear end portion of said pin may be received and slidably contained and said pin has a nut adjustably mounted thereon engageable with the forward end of the block.
